UNITED STATES PATENT OFFICE

2,578,161

AGITATOR FOR SPREADER STOKER FEEDERS

Herbert Leonard Wagner, Detroit, Mich., assignor to Detroit Stoker Company, Monroe, Mich., a corporation of Michigan

Application October 11, 1948, Serial No. 53,934

3 Claims. (Cl. 214—18.3)

1

The invention relates to stokers of the sprinkler type in which the fuel is thrown by a rotary impeller into the furnace chamber to be deposited over the fuel bed on the grate therein. More particularly, the invention relates to sprinkler stokers of the type disclosed in Patent No. 2,004,363 to R. L. Beers, issued June 16, 1935. In this construction the fuel from a hopper is fed by a reciprocating ram over a spill plate, and is dropped therefrom into the path of the rotary impeller. The forward edge of this spill plate is adjusted into predetermined relation to the vertical plane of the impeller axis, so that fuel dropping over this edge will contact with the impeller blades when at a predetermined angle. This determines the trajectory of the fuel hurled by the blades, and is important to the proper distribution of the fuel over the grate.

One difficulty which has been encountered in the operation of such stokers is that where the fuel is relatively fine and in a moist condition it has a tendency to pack and form a coherent mass. Consequently, when advanced by the ram it may be projected beyond the edge of the spill plate a considerable distance before breaking off and falling. Thus the angle of the blade when contacting the fuel is not the same as is the case where the plane of falling is adjacent to the edge of the spill plate, which results in unsatisfactory distribution of the fuel.

It is the object of the invention to overcome this defeat, and to this end the invention consists in the construction as hereinafter set forth.

In the drawings:

Fig. 1 is a vertical longitudinal section through my improved structure;

Fig. 2 is a cross-section substantially on line 2—2, Fig. 1;

Fig. 3 is a side elevation.

A is the rotary impeller, which is mounted upon a shaft B to rotate within a segmental cylindrical housing C having an open segment in communication with an opening D into the furnace. The fuel is supplied from a hopper E and rests therein upon a bottom plate or shelf F, which latter extends over the housing C and constitutes a spill plate. G is a ram resting upon the shelf F and reciprocated by suitable means, such as a rock shaft H and an upwardly extending rock arm I pivotally engaging the ram. The rock shaft H is actuated by an external rock arm K which, in turn, is actuated by a rod L engaging an eccentric L' on a shaft M. The shaft M is driven from the shaft B by a suitable step down gearing (not shown) and during each revolution

effects a complete reciprocation of the ram. Fuel is pushed off from the spill plate during each forward movement of the ram and if free will fall in a plane adjacent thereto. However, as above described, the fuel may be in a packed condition where instead of falling immediately it will be projected for a considerable distance beyond the edge of the spill plate before breaking off.

With my improved construction I provide means for breaking the cohesion between the portion of the fuel directly above and supported upon the spill plate, and that portion which is projected beyond the forward edge of the spill plate. This permits the fuel to freely fall in a plane which is determined by the adjustment of the spill plate. As specifically illustrated, the means for accomplishing this preferably comprises a rod N extending across the stoker slightly in advance of the forward edge of the plate, which rod has connected at its opposite ends upwardly extending arms N' passing through apertures O in the top plate O'. The upper ends of the arms N' are pivotally connected to rock arms P upon a rock shaft P', which shaft has an actuating rock arm P² connected by a rod Q to a crank pin Q' on the eccentric L'. The arrangement is such that each rotation of the eccentric L' will rock the shaft P' and cause a vertical reciprocation of the arms N' and rod N. The movement of the rod is also timed with the movement of the ram, so that during the forward movement of the ram the rod N will be pressed downward against any portion of the fuel projecting beyond the forward edge of the spill plate thereby freeing this portion from the portion following.

The stoker is preferably provided with means for adjusting the amplitude of movement of the ram which, as specifically illustrated and as shown in my prior Patent No. 2,004,363, comprises a pin L² on the outer end of the rock arm L, which engages an arcuate slot K' in the rock arm K to be adjustable in said slot towards or from the shaft H. A link R connects the pin L² with a lever S, which may be moved into different positions of adjustment, and is retained in each by a bar T having notches T' engaging a pin T² on the lever S.

What I claim as my invention is:

1. In a stoker of the sprinkler type, the combination with a rotary impeller, a spill plate on which fuel is deposited and a ram for advancing fuel on said spill plate; of a rod extending transversely across slightly in advance of the forward

edge of said spill plate, and mechanism timed with the advancement of said ram for pressing said rod downward to sever the portion of the fuel projected beyond the forward edge of said spill plate from the following portion.

2. In a stoker of the sprinkler type, the combination with a rotary impeller, a spill plate on which the fuel is deposited, and a ram for pushing the fuel on said plate beyond the forward edge thereof; of a rod extending transversely across slightly in advance of said forward edge of the spill plate, and mechanism for vertically reciprocating said rod to successively press downward and break off portions of the fuel projecting beyond said forward edge.

3. The construction as in claim 2 in which the reciprocating mechanism for said rod in-

cludes vertically extending links at opposite ends of said rod, a rock shaft, rock arms on said rock shaft pivotally connected to the upper ends of said links, an actuating rock arm for said rock shaft, a continuously rotating shaft, and a rod connected to said actuating rock arm and having an eccentric connection to said rotating shaft.
